UNITED STATES PATENT OFFICE.

EDGAR D. HUME, OF COLLINGSWOOD, NEW JERSEY, ASSIGNOR TO SUMMIT THREAD COMPANY, OF EAST HAMPTON, CONNECTICUT, A CORPORATION OF MAINE.

SEWING-MACHINE SHUTTLE.

Application filed July 28, 1922. Serial No. 578,030.

To all whom it may concern:

Be it known that I, EDGAR D. HUME, a citizen of the United States, residing at Collingswood, in the county of Camden and 5 State of New Jersey, have invented new and useful Improvements in Sewing-Machine Shuttles, of which the following is a specification.

This invention relates to a shuttle which 10 comprises a body forming a bobbin case adapted to receive and permit the rotation of a bobbin, the case including a central bobbin post on which the hub or core of the bobbin is adapted to rotate. 15 The object of the invention is to adapt a shuttle characterized as stated, and adapted, as originally constructed, to be used with a metal bobbin, composed of a flanged metal spool and a winding of thread thereon, to be 20 conveniently modified to adapt it for use with a ready-wound bobbin, composed of a flangeless cop tube and a universally-wound winding of thread thereon, the shuttle, when so adapted, including a spring-pressed metal 25 disk bearing yieldingly on the inner end of the bobbin, and preventing the entanglement or confinement of loose coils of thread displaced from the winding.

The invention is characterized by the improved means hereinafter described and 30 claimed, whereby said disk is confined in the case, so that it is movable outward only to a predetermined extent, by a spring seated on the inner side portion of the shuttle body, and is prevented from being displaced 35 inward sufficiently to objectionably compress said spring.

Of the accompanying drawings forming a part of this specification,—

40 Figures 1 and 2 are opposite side views, somewhat enlarged, of a shuttle embodying the invention.

Figure 3 is a more enlarged section on line 3—3 of Figure 1.

45 Figure 4 is a view similar to Figure 3, the bobbin being removed.

Figure 5 is a fragmentary perspective view, showing the bobbin post and a part of the inner side portion of the shuttle body.

50 Figure 6 is a perspective view showing the sleeve forming the post enlargement and abutment shoulder hereinafter described.

Figure 7 is a perspective view, showing the stop sleeve hereinafter described.

Figure 8 is a perspective view, showing 55 the bobbin-supporting disk.

Figure 9 is a sectional view of the shuttle without the parts characterizing the invention.

The same reference characters indicate the 60 same parts in all of the figures.

The body of a shuttle to which the improvements characterizing my invention are applied includes an inner side portion 12, forming the inner end of a bobbin case, a circular 65 curb 13, forming the bobbin case margin, and a central tubular post 14, concentric with the curb. The parts 12, 13 and 14 form an annular space, which is open at one end, and is adapted to receive a bobbin which is 70 rotatable on the post.

As shown by Figure 9, the shuttle is adapted to be used without the abutment shoulder, the stop sleeve, the bobbin-supporting disk, and the spring hereinafter described, the 75 metal hub of a flange bobbin spool being applied to the post, and releasably confined by a latch arm 16, having a cam-shaped inner end 17, connected by a pivot stud 18 with the outer end of the post. The latch may be 80 confined either in the position shown by Figures 4 and 9, or in that shown by Figure 3, by a plunger 19, pressed by a spring 20 against the cam-shaped end 17. Said plunger is usually provided with a bobbin-ejecting finger 21, movable in a slot 22 in the post.

The construction shown by Figure 9, including the parts thus far described, as well as the parts shown by the drawings, and not described hereinafter, is common and well known, and is adapted for use with a so-called metal bobbin, which is confined in the case by the latch when the latter is in the position shown by Figure 3, and is released 90 and partly ejected by the finger 21, when the latch is moved to the position shown by Figure 4.

In carrying out my invention I adapt the shuttle for use with a ready-wound bobbin, 100 composed of a cop tube 24, and a thread winding 25, as next described.

I provide the inner end portion of the post 14 with an enlargement forming an out-

wardly facing abutment shoulder 26, said enlargement being preferably a separate part, and composed of a resilient contractile inner sleeve 27, of spring steel, adapted to closely hug the post and be retained thereon by friction, so that it cannot be accidentally turned. The sleeve may have an opening 28, permitting movements of the ejecting finger 21, so that the sleeve may be present on the post when the shuttle is used with a metal bobbin.

The abutment shoulder 26 is formed by the outer end of the sleeve, and is thinner or narrower than the stop shoulder herein-after described.

A smooth-surfaced disk 29 of sheet steel, or other material, is provided with a central orifice 30, having a sliding fit on the enlargement 27. Before placing the disk on the enlargement, I seat a volute spring 31, of crowning form, on the side portion 12, the inner convolution of the spring embracing the enlargement. I then place the disk 29 on the enlargement of the post, the disk resting on the spring. Finally I apply to the outer portion of the post a resilient contractile outer stop sleeve 32, which is preferably divided diagonally at one side as shown at 33, and is preferably made of tempered steel. The thickness of the stop sleeve 32 is greater than that of the inner sleeve 27, so that the inner end of the stop sleeve constitutes an inwardly facing stop shoulder, which bears on and overhangs the abutment shoulder 26, and is adapted to arrest the disk 29 in the position shown by Figure 4.

The stop sleeve frictionally hugs the post, so that it is not accidentally movable thereon. The abutment shoulder limits the inward movement of the stop sleeve on the post, so that the stop sleeve cannot be pressed inward sufficiently to unduly compress the spring 31.

The margin of the disk 29 has a sliding fit on the inner surface of the curb 13, and prevents coils of thread from being entangled with the spring. The disk frictionally controls the rotation of the bobbin and prevents undesirably loose rotation thereof.

It will be seen that the parts characterizing my invention may be quickly and conveniently applied to a shuttle body adapted for use with a metal bobbin, to adapt the shuttle for use with a ready-wound bobbin.

The enlargement which forms the abutment shoulder 26 may be an integral part of the post, if desired.

I claim:

1. In a sewing machine shuttle, the combination with a body including a side portion, a circular curb, a central post, and means adapted to confine a bobbin on the post and adjustable to and from operative position, of a sleeve adapted to be positioned about the inner end of the post, a disk fitted on the sleeve and free to move longitudinally thereof, a stop detachably engaged with the post between the outer end thereof and said sleeve, and a spring interposed between the disk and side portion of the shuttle body, the stop limiting outward movement of the disk under pressure of the spring and the sleeve at the inner end of the post providing an abutment limiting inward movement of the stop.

2. In a sewing machine shuttle, the combination with a body including a side portion, a circular curb, a central tubular post and means adapted to confine a bobbin on the post and adjustable to and from operative position, of a disk surrounding the post adjacent the side portion of the shuttle body and free to move longitudinally of the post, a spring interposed between the disk and said side portion of the body, a sleeve adjustable on the post and constituting a stop to limit outward movement of the disk under pressure of the spring, and means for limiting inward movement of said sleeve, for the purpose described.

3. In a sewing machine shuttle, the combination with a body including a side portion, a circular curb, a central tubular post and means adapted to confine a bobbin on the post and adjustable to and from operative position, of a disk surrounding the post adjacent the side portion of the shuttle body and extending substantially to the circular curb of said body, a spring interposed between the disk and side portion of the body, a sleeve frictionally engaging the post and constituting a stop limiting outward movement of the disk under the action of the spring, and an abutment on the post limiting inward movement of said sleeve.

In testimony whereof I have affixed my signature.

EDGAR D. HUME.
